TEXTILE MACHINERY

Coy Lester Huffman, Greenville, S. C.

Application January 2, 1943, Serial No. 471,165

8 Claims. (Cl. 139—151)

The present invention relates to improvements in elements used in textile machinery such, for instance, as wooden picker sticks, lug sticks, lug straps, check and pick sticks, shuttle binders, top cleaner boards for spinning frames and the like.

In the past it has been the practice to reinforce these elements by passing rivets, bolts, and the like, through the same. However, these fastening elements have been found to be unsatisfactory, due primarily to the fact that the wooden parts, which are kiln or air-dried, contract or shrink to a certain extent and this causes the metal rivets and bolts, even though tight when first placed in the wood, to become loose, due to the contraction. Since there is usually considerable pressure applied to these wooden elements, it is not uncommon for them to split soon after they are installed. Substantial expense is, therefore, incurred in replacing split or broken parts.

The present invention is designed to eliminate this objectionable feature and this is accomplished by providing dowel pins to take the place of the rivets and bolts. These pins are preferably inserted into the wooden elements transversely and diagonally thereof. When dowel pins are inserted in a picker stick in this manner, they will hold against any pressure arising from the iron stud upon which the stick works, and thereby prevent splitting of the stick. This is also true of the other wooden elements, such as lug sticks, shuttle binders, and the like. This greatly lengthens the life of these elements, and since the life of a picker stick will possibly be eighteen months, if splitting is prevented, it will be apparent that the present invention materially reduces the cost of maintenance of a textile plant. In fact, it has been found from actual experience that the present invention will reduce possibly as much as fifty percent of the number of wooden elements used.

The use of dowel pins, furthermore, eliminates the objectionable feature of catching lint on the metal rivets or heads of the bolts, which ordinarily is the cause of further trouble. Also, the employment of wooden dowel pins has the advantage of economy at this particular time, since it is increasingly difficult to secure bolts, rivets, and other metal fastening elements.

With the foregoing and other objects in view, the invention will now be more fully described, reference being had to the accompanying drawings in which:

Figure 1 is a face view of a picker stick provided with diagonally arranged dowels about the pivotal hole thereof.

Figure 2 is a similar view of an old style picker stick equipped with a rivet.

Figure 3 is an enlarged fragmental section on the line of the dowels of Figure 1.

Figure 4 is an enlarged edge view of that portion of the picker stick shown in Figure 3.

Figure 5 is a face view of a lug stick provided with dowels similarly arranged as in Figure 1.

Figure 6 is a similar view of an old style lug stick.

Figure 7 is a side view of a shuttle binder with a dowel arranged diagonally between the pivotal hole and the adjacent end thereof.

Figure 8 is a plan view thereof, and

Figure 9 is a side view of an old style of shuttle binder.

Referring to the drawings, and particularly Figures 1 to 4, there is disclosed an embodiment in which the present invention is applied to a picker stick. In this connection, Figure 2 discloses the old prior art type of picker stick 10 in which the usual bolt hole 11 is provided adjacent one end of the stick and about which the stick pivots. Ordinarily, pressure is applied to the stick at this point and in the past it has been the usual practice to insert either bolts or rivets 12 through opposite longitudinal edges of the stick and transversely to the bolt hole 11. While these sticks are usually kilned or air-dried, nevertheless it has been found that in spite of all precautions, there is always a certain amount of contraction. When metal rivets are used such as the rivet 12, these usually become loose even though they are tightly secured to the stick when first placed in the wood. Figure 2 illustrates the rivet after the stick has shrunk or contracted to a certain extent, so as to leave a space 13 between the edge 14 of the stick and the head 15 of the rivet. Under these conditions, the pressure which is applied to the stick at the pivot point 11 very quickly effects a splitting of the stick between the bolt hole 11 and the adjacent end of the stick.

Referring to Figure 6, there is disclosed a prior form of lug stick 16 which has split at the point 17 due to the pressure applied at the pivot point 18. This stick 16, similar to the picker stick 10, has shrunk or contracted after the rivet 19 has been applied thereto, and it has been ascertained from actual practice that the splitting occurs soon after the contraction of the stick and the loosening of the bolt due to said contraction.

Ordinarily, a picker stick and lug stick will last substantially eighteen months in constant use if the stick does not split or fracture. The present invention, therefore, is designed to elimi-

nate this objectionable feature and to provide means which will prevent the splitting of the sticks as well as other wooden elements used in the textile industry. This is accomplished by providing the picker stick 20 with a pair of dowel-receiving holes 21 and 21' (see Fig. 3), each of which passes transversely through the picker stick intermediate the side faces 22 and 23 thereof. Furthermore, these dowel holes are positioned on opposite sides of the bolt hole 24 and extend diagonally through the stick intermediate the side faces thereof. While these holes are shown as extending at substantially an angle of 45°, it is to be understood that the angle may vary as desired and according to the width of the picker stick or other element which is being reinforced.

A pair of dowels 25 and 26 are then inserted within the holes 21 and 21', respectively. While these pins may be formed of any desired material, such as wood, metal, plastic, or the like, I prefer to use hickory pins which are glued into the holes. Any pressure arising from the iron stud or pivot upon which the picker stick works, will be exerted against these pins. However, the pins being inserted diagonally and transversely of the picker stick will resist any effort of the stick to split and will, therefore, prolong and greatly increase the life of the stick over the prior type of picker stick wherein rivets or bolts are used as reinforcing means.

While the preferred embodiment discloses a pair of dowels, it is to be understood that if desired a single dowel pin may be utilized and in this connection it is preferable that the pin be inserted in a hole positioned between bolt hole 24 and the adjacent end of the stick, such, for instance, as the dowel pin 26. It is to be further understood that a plurality or more than two dowel pins may be utilized to reinforce the picker stick.

Referring to Figure 5, a type of reinforcing means similar to that illustrated in Figures 1, 3, and 4, is applied to the lug stick 16. In this connection, dowel holes 27 and 28 are formed in the lug stick and these holes pass diagonally therethrough intermediate the side faces of the stick and upon opposite sides of the bolt hole 18. Dowels 29 and 30, similar to the dowels 25 and 26, are glued into the holes 27 and 28 and resist any pressure exerted at the pivot 18 which would tend to split the lug stick at this point, such as illustrated in Figure 6.

In addition to the picker and lug sticks illustrated in Figures 1 to 6, there is also disclosed reinforcing means for a shuttle binder 31. In this connection, the bolt hole 32 upon which the binder pivots, extends transversely through one of the reduced end portions 33 of the binder. In this arrangement, only one dowel pin receiving hole 34 is disclosed and this also passes diagonally through the reduced end 33 of the shuttle binder and also transversely of the bolt hole. A dowel pin 35 is secured in the hole 34 and it will be observed that the angle at which this is inserted is somewhat less than the angle at which the dowel pins of the picker and lug sticks are inserted. This is due primarily to the reduced thickness of the wood at this point. However, I have ascertained that when a dowel pin is inserted at such an angle, all pressure exerted at this point, which would tend to split the binder, is resisted by the pin because of the fact that it is inserted diagonally and transversely of the binder.

In Figure 9, there is disclosed the old type of binder wherein a screw 36 is used to reinforce the binder at the edge adjacent the pivot hole 37. Similarly to the rivet reinforced picker and lug sticks shown in Figures 2 and 6, the pressure exerted at this point is sufficient to split the end of the binder notwithstanding the use of screws or like elements 36. However, when one or more dowels are inserted transversely and diagonally of the wooden element to which it is applied, this is sufficient to prevent splitting and to insure repeated use of the element.

It is to be understood that the invention is not limited to the details of construction shown in the drawings, and that the phraseology employed in the specification is for the purpose of description and not of limitation.

I claim:

1. A wooden picker stick for looms having a bolt-receiving hole passing transversely therethrough, said picker stick having a dowel pin-receiving hole passing diagonally therethrough adjacent to and transversely of the bolt hole, and a dowel pin located in said dowel hole and constituting a reinforcing element to prevent splitting of the picker stick.

2. A wooden picker stick for looms having a bolt-receiving hole passing transversely therethrough, said picker stick having a pair of dowel-receiving holes passing diagonally therethrough upon opposite sides of and transversely of the bolt hole, and dowel pins located in said dowel holes and constituting reinforcing elements to prevent splitting of the picker stick.

3. A wooden picker stick for looms having a bolt-receiving hole passing through and transversely of the side faces of the picker stick and constituting a pivot upon which the picker stick is adapted to fulcrum, said picker stick having a dowel pin-receiving hole passing diagonally therethrough intermediate the side faces of the picker stick and adjacent the bolt hole, and a dowel pin located in said dowel hole and constituting a reinforcing element to prevent splitting of the picker stick in the vicinity of the bolt hole.

4. A wooden picker stick for looms having a bolt-receiving hole passing through and transversely of the side faces of the picker stick and constituting a pivot upon which the picker stick is adapted to fulcrum, said picker stick having a pair of dowel-receiving holes passing diagonally therethrough intermediate the side faces of the picker stick and located upon opposite sides of the bolt hole, and dowel pins located in said dowel holes and constituting reinforcing elements to prevent splitting of the picker stick in the vicinity of the bolt hole.

5. A wooden picker stick for looms having a bolt-receiving hole passing through and transversely of the side faces of the picker stick and constituting a pivot upon which the picker stick is adapted to fulcrum, said picker stick having a pair of dowel-receiving holes passing diagonally therethrough intermediate the side faces of the picker stick and located upon opposite sides of the bolt hole, and dowel pins located in said dowel holes and constituting reinforcing elements to prevent splitting of the picker stick in the vicinity of the bolt hole, said dowel pins being arranged at such an angle to the longitudinal edges of the picker stick that opposite ends of the pins overlap each other and substantially overlie the bolt hole.

6. A wooden element for use in textile machinery having a hole passing transversely there-

through and constituting a pivot upon which the element is adapted to fulcrum, said element having a dowel pin-receiving hole passing diagonally therethrough adjacent to and transversely of the bolt hole, and a dowel pin located in said dowel hole and constituting a reinforcing means to prevent splitting of said element.

7. A wooden lug stick for looms having a bolt-receiving hole passing transversely therethrough adjacent one end of the lug stick, said lug stick having a dowel pin-receiving hole passing diagonally therethrough transversely of the bolt hole and positioned between the bolt hole and the adjacent end of the stick, and a dowel pin

located in said dowel hole and constituting a reinforcing element to prevent splitting of the lug stick.

5 8. A shuttle binder for looms having a bolt-receiving hole passing transversely therethrough adjacent one of the narrow end portions of the binder, said shuttle binder having a dowel pin-receiving hole passing diagonally therethrough transversely of the bolt hole and positioned between the bolt hole and the adjacent end of the binder, and a dowel pin located in said dowel hole and constituting a reinforcing element to prevent splitting of the binder.

COY LESTER HUFFMAN.
